UNITED STATES PATENT OFFICE.

ROBERT ARTHUR JOHNSTONE, OF NESS CITY, KANSAS.

RAZOR-BLADE HOLDER.

1,212,956.

Specification of Letters Patent. Patented Jan. 16, 1917.

Application filed June 13, 1916. Serial No. 103,524.

To all whom it may concern:

Be it known that I, ROBERT A. JOHNSTONE, a citizen of the United States, and a resident of Ness City, in the county of Ness and State of Kansas, have invented 5 a certain new and useful Improvement in Razor-Blade Holders, of which the following is a specification.

This invention is an improvement in 10 razors, and it has particular reference to razors of the so-called safety type.

An object of the invention is the provision of an improved holder for a detachable blade, wherein an arm of the razor has a 15 socket for the reception of a blade carrier and ejector removably mounted therein and of novel construction, and having a clamping device associated therewith for retaining the blade in adjusted position.

Another object is to provide a device of 20 this character which is simple in construction, easy to manufacture, and wherein the blade is readily and quickly removable when it is desired to replace the same.

The inventive idea involved is capable of 25 receiving a variety of mechanical expressions, one of which for the purpose of illustrating the invention, is shown in the accompanying drawing wherein—

Figure 1 is a side elevation of the razor 30 constructed in accordance with the invention. Fig. 2 is a longitudinal section on the line 2—2 of Fig. 1. Fig. 3 is a transverse section on the line 3—3 of Fig. 1. Fig. 4 is a similar section on the line 4—4 35 of Fig. 1. Fig. 5 is a detail perspective view of the parts separated.

The invention is illustrated in connection 40 with a razor of the pivoted handle type, but it is of course understood that the same can be used in connection with any other type of razor involving a detachable blade construction.

There is illustrated in the accompanying 45 drawing what is now believed to be a preferred form of the invention, wherein the handle 10 is pivoted at 11 to the arm 12, which is preferably made of metal bent upon itself as indicated, to provide a socket 13 extending substantially the length thereof. At the outer end of the arm 12 the same is provided with oppositely disposed jaws or blade guides 14, for receiving the razor blade 15 therebetween. These jaws 50 are preferably formed integral with the arm 12, and are spaced a less distance apart

than the width of the socket 13, so that the inner surfaces of said jaws will tightly engage the blade 15 when the same is adjusted in position.

60

The blade 15 is preferably provided along its inner longitudinal edge with a filling piece 16 to provide an enlarged portion adapted to fit snugly in the socket 13 of the arm 12. A carrying and ejecting device 65 17 is associated with the blade 15 and is preferably in the form of an elongated bar cut away at one end to provide a reduced extension 18 substantially equal in length to that of the blade 15 and having at its 70 reduced extremity a transverse flange stop 19 between which and the shoulder formed by the reduced portion, the blade 15 is adapted to fit. When adjusting the razor blade in position, the enlarged end of the 75 carrying and ejecting device 17 is first inserted into the socket 13, then moved longitudinally thereof, until the inner end of the razor blade also is in alinement with the socket 13, whereupon the carrying device 80 and blade may be further pushed inwardly into said socket until the inner end of the device 17 contacts the inner end of the said socket. When in this position the flange stop 19 will engage the outer extremity of the arm 12, and in order to facilitate the removal of the blade, the said arm is notched as indicated at 20, in order that the operator may insert a fingernail into engagement with the end of the said stop 85 90 flange 19 and thus withdraw the carrying and ejecting device from the socket 13.

In order to securely retain the blade 15 in its adjusted position, there is provided a clamping plate 21 having at each end thereof a guide 22 between which and the body of said plate is received the jaws or blade-guide 14. One longitudinal edge of the clamping plate 21 is provided with the usual guard fingers 23, while the other edge 100 thereof is provided with an extension 24 carrying a lug 25 adjacent its outer end, which is adapted to engage either one of the openings 26 formed in the arm 12 intermediate the ends of the jaws 14. This extension 24 is preferably resilient, and when the clamping plate is in position the lug 25 will snap into the opening 26, and thus retain the clamping plate in position.

105 What is claimed is:

110 1. A razor including an arm having parallel blade engaging jaws at one end, and

5 a socket extending longitudinally thereof, a blade mounted between said jaws, and a carrying and ejecting device for said blade including a flat elongated member having one of its edges reduced to provide a recess of a length substantially equal to that of said blade whereby to receive a portion thereof, said device being inserted into said socket and having its reduced portion interposed between the inner longitudinal end of said jaws and the inner edge of said blade.

10 2. A razor including an arm having parallel blade engaging jaws at one end and a socket extending longitudinally thereof, a blade mounted between said jaws, and a carrying and ejecting device for said blade

including a flat elongated member having one of its edges reduced to provide a recess of a length substantially equal to that of said blade whereby to receive a portion thereof, said device being inserted into said socket and having its reduced portion interposed between the inner longitudinal end of said jaws and the inner edge of said blade, and a transverse stop flange carried by the outer extremity of said elongated member and adapted to engage the adjacent transverse edges of said jaws.

ROBERT ARTHUR JOHNSTONE.
